The ornamental design for a fingernail gel curing lamp, as
shown and described.

DESCRIPTION

FIG. 1 is a top perspective view of a fingernail gel curing
lamp showing our new design;

FIG. 2 is a bottom perspective view thereof;

FIG. 3 is front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

In FIGS. 1-8, the broken lines define the bounds of the
claimed design and form no part thereof.

1 Claim, 8 Drawing Sheets
